UNITED STATES PATENT OFFICE

2,186,787

RELEASE FOR IRONER SHOE

Joseph W. Jensen, Chicago, Ill., assignor to Electric Household Utilities Corporation, Chicago, Ill., a corporation of Illinois

Application April 16, 1937, Serial No. 137,183

17 Claims.

(Cl. 38—61)

The present invention pertains to ironing machines of the type adapted for domestic use, comprising a rotatable roll and a cooperating power actuated shoe adapted to be automatically moved toward and away from the roll by manipulation of a control member.

More particularly, the present invention is directed to a novel manually operable release for moving the ironer shoe away from the roll independently of power actuated mechanism. Devices of this general class are usually constructed to serve the function of an emergency release to be operated manually in the event that the motor driven mechanism becomes stalled, such as due to a sudden break in the electrical circuit. The necessity of such a device, under such circumstances, will be apparent because it may happen that the electrical current is broken at a time when the ironing machine is in operation with the ironer shoe in cooperating engagement with the roll, in ironing a piece of fabric or an article of apparel. In such case the fabric being ironed may be burned or damaged if means were not provided to manually back the shoe away from the roll. Another function of many commercial forms of releases of the character indicated, is to permit adjustment of the shoe to a position at which it may be swung about its mounting in an upwardly open horizontal position so that the ironing surface of the shoe may be employed for performing certain special ironing operations which are impossible to perform with the shoe in normal cooperating engagement with the roll, such as in ironing of puff sleeves of a dress, pressing of neckties, etc.

One of the objects of this invention is to provide a novel and an improved form of release of the character indicated in which the control handle for actuating the release normally extends in an upward direction and is adaptable to be telescoped downwardly to render the total ironing machine construction relatively compact and enabling it to be housed or enclosed within a cabinet of minimum dimensions.

Another object resides in the provision of an improved release of the character indicated having means associated therewith for varying the effective pressure of the shoe against the roll.

A further object resides in the provision of an improved device of the character indicated including means adapted for resiliently moving the shoe away from the roll when the device has been operated.

Still another object is to provide an improved release of the character indicated having an up-

wardly extending control handle adapted to be telescoped downwardly to a position for interlocking engagement with parts of the control device for precluding operation of the device.

A still further object is to provide an improved release of the character indicated, having a manually operable control handle adapted, when the shoe is backed away from the roll, to swing the shoe about its support to dispose its operating surface in an upwardly facing direction for performing certain special ironing operations.

And a still further object of this invention is to provide an improved device of the character indicated which is simple in construction, positive in operation, easily accessible for manipulation, and capable of economical manufacture.

Other objects and advantages of the present invention will be apparent from the following description, taken in connection with the accompanying drawings in which:

Fig. 1 is a fragmentary view in side elevation of a domestic, cabinet type, ironing machine, provided with a release device, embodying the present invention, parts being broken away to show details of construction.

Fig. 2 is an enlarged vertical sectional view through the release mechanism, taken substantially as indicated at line 2—2 on Fig. 1, with roll and shoe in end elevation, and part of shoe actuating mechanism in section, showing the release mechanism in an inactive position of adjustment and the shoe backed away from the roll by power driven mechanism.

Fig. 3 is a vertical sectional view similar to Fig. 2 showing the shoe in cooperating engagement with the roll.

Fig. 4 is a vertical sectional view similar to Fig. 3 showing the relation of the parts of the release when actuated, with the shoe carried back out of engagement with the roll.

Fig. 5 is a vertical sectional view through the control device, with the parts shown at operated position of adjustment with the shoe backed away from the roll and tilted to dispose its operating surface in an upwardly open direction.

Fig. 6 is a fragmentary view showing cooperating stop surfaces of the shoe bracket and supporting arm by virtue of which the shoe may be arrested in an upwardly open position.

Fig. 7 is a fragmentary rear view of the ironing machine showing the release device in rear elevation.

Fig. 8 is a transverse sectional view taken substantially as indicated at line 8—8 on Fig. 2.

Fig. 9 is an elevational view of the release cam, taken as indicated at line 8—8 on Fig. 2.

Fig. 10 is a view similar to Fig. 3 showing the control handle telescoped downwardly in interlocking engagement with other parts, to prevent actuation of the release.

Fig. 11 is a transverse section through the release device, taken at line 11—11 on Fig. 10.

In the illustrated embodiment of my invention I have disclosed an ironing machine of the folding type wherein the ironing mechanism is associated with a cabinet in a manner which permits it to be folded within the cabinet when not in use, or withdrawn into operating position outside of the cabinet, as seen in Fig. 1 of the drawings. It will be manifest, however, and as will be apparent from the following description, that the present invention is not to be limited for use with a folding type ironer, but is readily adaptable to various other types of ironer units, such as a portable type, or table top ironer units.

Referring now in detail to the drawings, the reference character 10 indicates a cabinet of substantially rectangular box-like form, of substantially greater height than width or depth for an ironer mechanism indicated generally at 11, mounted on a baseboard or support 12, the ironer mechanism and the baseboard being movable as a unit for folding within the cabinet when not in use. The ironer mechanism comprises a roll 13 and a cooperating shoe 14, the former being totally supported at one end by a housing or standard 15 mounted on the inner end of the baseboard 12, as seen in Fig. 1. The shoe 14 is of a conventional construction and may be heated electrically. It is to be understood that the housing 15 contains suitable driving and control mechanism for rotating the roll and for moving the shoe into and out of cooperating relation therewith, and said mechanism is driven by an electric motor housed within a casing 16 secured to the under side of the baseboard 12. The motor includes an upwardly extending shaft 17 to the upper end of which is rigidly attached a driving pinion 18 meshed with a gear 19 on the lower end of a main vertically disposed drive shaft 20 journaled in suitable bearings within the housing 15. Connected to the upper end of the main drive shaft 20 is a driving worm 21 operatively engaged with a worm gear 22, adapted for operable engagement with suitable driving and control mechanism, such as of the type disclosed in my co-pending application Serial No. 134,541 filed April 2, 1937. The mechanism within the housing 15 as disclosed in said co-pending application is rendered operable by a hand control lever 24 which serves normally upon one actuation to move the shoe 14, into operative engagement with the roll, and upon the next successive actuation to move the shoe back away from the roll. Said mechanism may be understood to be such as to normally cause rotation of the roll substantially when the shoe engages the same, and substantially causes arresting of the roll at the time the shoe commences to back away from said roll. However, when it is desired that the roll remain stationary irrespective of the actuation of the shoe, the mechanism for driving the roll may be controlled by the handle 26 which disengages drive connections to the roll, as indicated in my co-pending application.

The cabinet 10 is provided with a door opening 18 through which the ironer unit passes when it is moved into and out of the cabinet. Suitable means is provided for guiding the ironer unit

during such movement for causing folding of the unit in vertical position when it has been moved completely into the cabinet and to unfold the same in a horizontal position as seen in Fig. 1 when entirely withdrawn from the cabinet. Although the mechanism for performing these functions constitutes no part of the present invention, it will be briefly described as follows:

The ironer unit is guided in its movement by rails 28 and 29 which may be understood to be 10 duplicated on opposite sides of the wall cabinet, and links 30 and 31 cooperate with the rail 29 while supporting struts 32 carried at opposite sides of the end of the baseboard 12 are provided with rollers 33 which travel in the channel rails 15 28. In the extended position of the ironer unit the inner end of the baseboard 12 is supported from the rails 28 by the struts 32 and the outer end of the baseboard is supported by a foldable hinged leg 35 which may be collapsed against the 20 under side of the baseboard 12 when the ironer is disposed in folded position in the cabinet. The leg 35 is automatically folded during the movement of the ironer into the cabinet and any suitable mechanism may be employed for this purpose. In the drawings this mechanism includes a link 36 connected at one end to the leg, while the opposite end is connected to a cam 37 which in turn is actuated by the link 30.

The roll 13 is of a conventional construction 30 including a tubular metallic supporting body 40 around which is wrapped one or more layers of resilient material or padding 41 and which may be understood to be covered by an outer jacket or wrapper of suitable fabric such as muslin. 35 Mounted in opposite ends of the tubular body 40 are dish-shaped elements 43 having journaled support on a stationary tubular sleeve 44 which extends longitudinally and centrally in the tubular body and is rigidly anchored at one end in the housing 15, providing journal support for the 40 roll 13. Extending longitudinally through the tubular sleeve is a roll drive shaft 46, one end of which extends into the housing 15 and is detachably engaged by the driving mechanism in said housing, as above referred to, while the opposite 45 end of said shaft extends through and beyond the dished end plate 43, at the outer or unsupported end of the roll. Rigidly mounted on the outer end of the shaft 46 is a sleeve 47 having a flange 48 rigidly attached to said end plate 43 so that rotation of the drive shaft 46 is transmitted through the sleeve 47 and flange 48 to the element 43 for causing rotation of the roll.

The shoe 14 which cooperates with roll 13 and is movable into and out of engagement therewith 55 is of elongated form and is of substantially the same length as the roll, and the operating face of said shoe is curved arcuately in cross-section to approximately the same curvature as the exterior surface of the roll. The shoe is supported 60 adjacent its longitudinal center by means comprising a bracket 50 rigidly secured to the back of the shoe and formed with a pair of rearwardly extending ears 50a journaled on a pivot pin 51, the axis of which extends substantially parallel 65 to the roll 13, the pivot pin being carried in a pair of ears 52a formed on the upper end of an upwardly extending supporting arm 52, the lower end of which arm is journaled on the end of a tubular rock shaft 54 which extends parallel to 70 and below the axis of the roll 13. The other end of the rock shaft extends into a rearward portion 15a of the housing 15. Surrounding the rock shaft is a tubular sleeve 55 rigidly secured at one

end in the housing portion 15^a, while its opposite end terminates adjacent the arm 52 and is surrounded by a bearing 56^a of a foot bracket 56 secured to the top of the baseboard 12. Said 5 foot bracket 56 thus assists in supporting the shoe 14, through the arm 52. Mounted in the opposite ends of the tubular sleeve 55 and surrounding the rock shaft 54 are bushings or bearings 57 which serve to properly support the rock 10 shaft centrally within the tubular sleeve.

Said housing 15 is formed with a tubular chamber 15^b substantially radial to the axis of the roll and extending in a rearward and downward direction below the rock shaft 54 as seen 15 in Fig. 3. Disposed within the chamber 15^b is a bolt 58 having a head 58^a, the under side of which is recessed to form a pocket for the end of a compression spring 59, the opposite end of which spring seats in a recess 60^a of an actuating 20 block 60 slidably mounted on the bolt and in the tubular chamber 15^b. The side wall of the block 60 is formed with a slot or opening 60^b into which extends the end of an actuating block or finger 62 rigidly secured to the end of the 25 tubular rock shaft 54. The lower end of the bolt is reduced in cross section to provide a shoulder 58^c against which is seated a washer 64 held in place by a nut 65, and places spring 59, under compression. The lower end of the chamber 15^b is closed by a threaded cap 66 formed with a recess 66^a to provide a seat for a compression coil spring 68 which circumscribes the lower end of the bolt and abuts against the washer 64.

35 The upper end of the head 58^a of the bolt is formed as a clevis 58^b and a roller 69 is interposed between the ears of the clevis and journaled on a pin 69^a. The spring 59 normally tends to urge the bolt 58, due to the engagement of 40 finger 62 in the block 60, in an upward direction so that the roller 69 is constantly in engagement with the periphery of a clover-leaf shaped cam 70, having three high portions 70^a and three alternate low portions 70^b. It is to be understood that upon successive actuations of 45 the controlling lever 24 the cam 70 is rotated one-sixth of a revolution to dispose either a high portion 70^a or a low portion 70^b of said cam into cooperative engagement with the roller 69, as discussed in my said co-pending application. Thus when the cam 70 is moving to a position as seen in Fig. 2, with the roller engaged with a low portion 70^b of the cam, the force acting on the 50 compression spring 59 is reduced and the coil spring 68 is free to move the bolt in an upward direction and through the block 60 and finger 62 causes rocking of the tubular shaft 54 in a direction for swinging the supporting arm 52 rearwardly, and moving the shoe 14 back, away 55 from the roll.

When pressure is exerted against the roller 69 by camming action due to readjustment of the cam 70, resulting from the manipulation of the control handle 24, so that a high point 70^a of 60 the cam aligns with the roller 69, as seen in Fig. 3, the bolt 58 is urged in a downward direction, and through the medium of the compression spring 59, the block 60 is urged downwardly which through the finger 62 causes rocking of the shaft 54 forwardly, swinging the arm 52 in a direction to move the shoe 14 into cooperative engagement with the roll, as seen in Fig. 3. It is to be understood that the shoe engages the roll prior to the high point 70^a of the cam, fully actuating the bolt 58 through roller 69, and that

further downward movement of the bolt 58 is permitted and the block 60 is urged against the finger 62 by the force of the increased compression of the spring 59, as the high point 70^a of the cam aligns with the roller 69, thus providing 5 resilient pressure of the shoe against the roll for insuring proper ironing or pressing operations upon fabrics, such as indicated generally at A in the drawings.

As above mentioned, it is essential to provide 10 some manual form of release which will permit movement of the shoe away from the roll in the event of an emergency such as when electrical current is suddenly cut off, and the shoe is in cooperative engagement with the roll. In the 15 present invention this release is directly associated with and is formed as a part of the support for the shoe on the rock shaft 54. The supporting arm 52 which as above mentioned is journaled at its lower end on the end of the rock 20 shaft, is formed with a pair of axially spaced-apart ears 52^b intermediate which is disposed a lever 72 surrounding the rock shaft 54 and rigidly clamped thereto by a machine screw 73 engaging cooperating ends of the body of the lever, 25 surrounding the shaft, as seen in the drawings. Said member 72 includes an arm 72^a which extends into a recess or slot formed in the lower end of an upwardly extending rod 74 which is 30 slidably mounted in the body of the arm 52. 35 The upper end of the rod carries a roller 75 journaled on a pin 76 on said rod, and co-acting with said roller is a cam 77, co-pivotedly mounted on the pivot pin 51 with the ears 50^a of the bracket 50. Said cam is formed with an upwardly extending boss 77^a to which is connected a manual control handle, including a rod 78 telescopically mounted in said boss and provided at its outer end with a knob 79. The lower end of the rod 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 wardly, which would reduce the pressure in ironing the final portion of the piece of fabric.

Resilient means is provided for normally urging the arm 52 rearwardly with respect to the lever bracket 72 and in the drawings said means is shown in the form of a compression spring 86 enclosed within a tubular body of a button 87, mounted in a recess 72^b on said lever, with the spring reacting against the under side of the button and the bottom of a recess, urging the head of the button against the arm 52. This spring-pressed button serves to operatively move the arm 52 together with the shoe 14 to the position seen in Fig. 4 when the cam 77 has been adjusted to the position seen in Fig. 4 by operation of the control handle. This action takes place by reason of the fact that the lever 72 remains stationary and the reactive forces against the temporarily fixed lever 72 caused by the spring pressed button 87, which may be understood to be sufficient to overcome the effect of gravity acting on the shoe 14, moves the arm 52, rearwardly together with said shoe, causing relative movement of the rod 74 with respect to said arm 52 so that the roller 75 is maintained in contact at all times with the operating surface of the cam 77.

The operating surface of the cam includes three re-entrant portions 77^c, 77^d, 77^e. As may be seen in Figs. 2 and 3 when the portion 77^c is in engagement with the roller 75, the parts are in normal operating condition so that the shoe 14 may be moved to and from cooperating engagement with the roll 13 by the drive mechanism under control of the lever 24. However, when it is desired to actuate the emergency release the control handle is swung rearwardly to a position as seen in Fig. 4, at which time the cam 77, aligns the re-entrant portion 77^d with the roller 75, permitting the arm 52 to swing rearwardly, by the spring pressed button 87, carrying the pivot pin 51 therewith, and withdrawing the shoe 14 back out of engagement with the roll, so as to permit removal of fabric from between the shoe and roll, in the event that the ironer drive mechanism is rendered inoperative, such as by breaking of the power circuit. In such position of adjustment of the release device, cooperating abutment surfaces 77^f of the cam 77 and 50^b of the bracket 50 are in engagement, as seen in Fig. 4, and further movement of the control handle in a downward direction is limited by reason of the fact that the lower edge of the shoe will contact the surface of the roll. This feature is important in that it definitely precludes the possibility of burning the wrist of the operator in reaching over the shoe and operating the control handle for swinging the shoe to an upwardly open position as seen in Fig. 5 for performing certain special ironing operations, such as ironing ruffles, puff sleeves of a garment, steaming of fabrics, etc. The release device may be reset by swinging the control handle in an upward direction to dispose the reentrant cam portion 77^e in registration with the roller 75, which moves rod 74 downwardly and moving the arm 52 forwardly to dispose the shoe in a rearward position of adjustment.

When it is desired to dispose the shoe in the position seen in Fig. 5, the shoe should first be backed away from the roll by the driving mechanism under control of lever 24 so that the shoe arrives at a position indicated in dotted lines at B in Fig. 5. Then upon actuation of the release by shifting the control handle rearwardly for

aligning reentrant portion 77^d of the cam with the roller 75, the shoe is moved rearwardly an additional amount to a position as indicated in dotted line at C in Fig. 5. Now the operator may by moving around to the back of the machine 5 grasp the control handle and swing it downwardly, and due to the abutment stops 77^f and 50^b of the cam and shoe bracket respectively, the shoe may be further rocked about the pivot pin 51 to the upwardly open position as seen in Fig. 10 at which position the shoe becomes arrested by engagement of stop shoulders 50^c on the respective ears 50^a of the bracket 50, engaging the surface of the arm 52 as seen in Fig. 6 of the drawings, and the reentrant portion 77^e of cam 77 is seated on the roller 75, tending to maintain the parts in such position of adjustment. It will be apparent that if desired, when the shoe is backed away from the roll by the power driven mechanism, the operator may by one continuous swing of the control handle back the shoe away from the roll an additional amount and rock the shoe to an upwardly facing position as seen in Fig. 5. The release may be quickly reset by merely swinging the control handle upwardly to 25 register reentrant portion 77^e of the cam with the roller 75, and disposing the shoe in a normal position for operation.

To conveniently vary the effective pressure of the shoe against the roll for performing the ironing operation I have provided an adjusting screw 90, located in the arm 72^a of the lever bracket, the end of which screw is adapted to engage the lower end of the rod 74 for moving it within the arm 52, and which due to the action of the spring 35 pressed button 87 against the arm 52 will tend to vary the relationship of the shoe 14 with respect to the roll. In other words, if the screw 90 is threaded upwardly, a substantial distance and thereby raising the rod 74, the effective pressure 40 of the shoe on the roll will be increased, and by withdrawing the screw so as to permit the rod 74 to move downwardly with respect to the lever arm 72^a, the effective pressure of the shoe on the roll is reduced. The screw 90 is maintained in 45 any position of adjustment by a coil spring 91 reacting between the head of the screw and the under side of lever arm 72^a. This is an important feature in that it permits an operator to make quick and easy adjustment of pressure to suit 50 desired ironing conditions.

The body of the arm 52 just above the spring button 83 formed with an integral strap or socket 52^c for receiving the lower end of the rod 74 of the control handle, as seen in Fig. 10, in which 55 position of adjustment the cam 77 is locked with respect to the arm 52 and the control handle occupies a telescoped compact position. This construction is particularly advantageous in connection with ironers of the folding cabinet type 60 wherein it is desired to maintain a cabinet of minimum dimensions. In such instances this control handle may serve as a convenient hand grasp for moving the ironer into and out of the cabinet, and when the ironer is in operating position outside of the cabinet the control handle may be withdrawn upwardly to normal operating position, and when not in use may be telescoped to the position seen in Fig. 10. Furthermore, when the control handle is in telescoped 70 position the knob portion thereof does not protrude appreciably above the shoe. This is of particular advantage in some instances when in ironing a piece of fabric, the body thereof is thrown back over the shoe as it is fed between the 75

roll and shoe, and hence the handle in such position will not interfere with proper training of the piece of fabric into the bight of the roll and shoe.

5 Although I have herein shown and described a preferred embodiment of my invention, manifestly it is capable of modification and rearrangement of parts without departing from the spirit and scope thereof. I do not, therefore, wish to 10 be understood as limiting this invention to the precise embodiment herein disclosed, except as it may be so limited by the appended claims.

I claim as my invention:

1. In an ironing machine, the combination with 15 a rotatable roll, a shoe, a rock shaft, power driven means for rocking said shaft, of means carried on said shaft and connected to the shoe for supporting and moving the latter into and out of cooperative relation to the roll upon rocking of 20 said shaft, said supporting means comprising an upwardly extending arm journaled at its lower end on said shaft, a manually movable cam pivotally connected to the upper end of the arm, a bracket rigidly attached to the shoe and pivotally 25 mounted on said arm about a horizontal axis, and means comprising a lever arm rigidly attached to the shaft, and a member slidably mounted in the upwardly extending arm and having opposite ends cooperatively engaging said lever and said 30 cam for controlling movement of the shoe toward or away from the roll, by movement of said cam, independently of said power driven means.

2. In an ironing machine, the combination with 35 a rotatable roll, a shoe, a rock shaft, power driven means for rocking said shaft, of means carried on said shaft and connected to the shoe for supporting and moving the latter into and out of cooperative relation to the roll upon rocking of 40 said shaft, said supporting means comprising an upwardly extending arm journaled at its lower end on said shaft, a manually movable cam pivotally connected to the upper end of the arm, a bracket rigidly attached to the shoe and pivotally 45 mounted on said arm about a horizontal axis, and means comprising a lever arm rigidly attached to the shaft, an upwardly extending member slidably mounted in the arm and having its 50 lower end cooperatively engaging the lever, and a roller at the upper end of said member and cooperatively engaging the cam, whereby the shoe is moved toward or away from the roll, by movement of the cam, independently of said power driven means.

3. In an ironing machine, the combination with 55 a rotatable roll, a shoe, a rock shaft, power driven means for rocking said shaft, of means carried on said shaft and connected to the shoe for supporting and moving the latter into and out of cooperative relation to the roll upon rocking of 60 said shaft, said supporting means comprising an upwardly extending arm journaled at its lower end on said shaft, a manually movable cam pivotally connected to the upper end of the arm, a bracket rigidly attached to the shoe and pivotally 65 mounted on said arm about a horizontal axis, and means rigidly connected to the rock shaft and coacting with the cam for controlling movement of the shoe toward or away from the roll by movement of said cam, independently of 70 said power driven means, said cam and bracket having cooperating stop surfaces adapted to be engaged when the cam is moved to a position to cause the shoe to be moved back from the roll, whereby further rotary movement of the cam swings the shoe upwardly about the pivot connection of said bracket.

4. In an ironing machine, the combination with 75 a rotatable roll, a shoe, a rock shaft, power driven means for rocking said shaft, of means carried on said shaft and connected to the shoe for supporting and moving the latter into and out of cooperative relation to the roll upon rocking of 80 said shaft, said supporting means comprising an upwardly extending arm journaled at its lower end on said shaft, a manually movable cam pivotally connected to the upper end of the arm on a horizontal axis, a bracket rigidly attached to the shoe and pivotally mounted on said arm co- 85 axially with said cam, and means rigidly connected to the rock shaft and coacting with the cam for controlling movement of the shoe toward or away from the roll by movement of said cam, independently of said power driven means.

5. In an ironing machine, the combination with 90 a rotatable roll, a shoe, a rock shaft, power driven means for rocking said shaft, of means carried on said shaft and connected to the shoe for supporting and moving the latter into and out of cooperative relation to the roll upon rocking of 95 said shaft, said supporting means comprising an upwardly extending arm journaled at its lower end on said shaft, a manually movable cam pivotally connected to the upper end of the arm on a horizontal axis, a bracket rigidly attached to the shoe and pivotally mounted on said arm co- 100 axially with said cam, and means rigidly connected to the rock shaft and coacting with the cam for controlling movement of the shoe toward or away from the roll by movement of said cam, independently of said power driven means.

6. In an ironing machine, the combination with 105 a rotatable roll, a shoe, a rock shaft, power driven means for rocking said shaft, of means carried on said shaft and connected to the shaft for supporting and moving the latter into and out of cooperative relation to the roll upon rocking of 110 said shaft, said supporting means comprising an upwardly extending arm journaled at its lower end on said shaft, manually movable means pivotally connected to the upper end of the arm, a bracket rigidly attached to the shoe and pivotally 115 mounted on said arm about a horizontal axis, means rigidly connected to the rock shaft and coacting with said manually movable means, and spring means acting on said arm and adapted, upon adjustment of the manually movable means in one position, to move said arm rearwardly to 120 back the shoe away from the roll.

7. In an ironing machine, the combination with 125 a rotatable roll, a shoe, a rock shaft, power driven means for rocking said shaft, of means carried on said shaft and connected to the shoe for supporting and moving the latter into and out of cooperative relation to the roll upon rocking of 130 said shaft, said supporting means comprising an upwardly extending arm journaled at its lower end on said shaft, a manually movable cam pivotally connected to the upper end of the arm, a bracket rigidly attached to the shoe and pivotally 135 mounted on said arm about a horizontal axis, and means comprising a lever arm rigidly attached to the shaft, a member slidably mounted in the arm and having opposite ends cooperatively en- 140

- gaging said lever and said cam, together with spring means acting on said arm and adapted in one position of adjustment of the cam for moving said arm rearwardly about the axis of the shaft and thereby moving the shoe away from the roll.

8. In an ironing machine, the combination with a rotatable roll, a shoe, a rock shaft, power driven means for rocking said shaft, of means carried on said shaft and connected to the shoe for supporting and moving the latter into and out of cooperative relation to the roll upon rocking of said shaft, said supporting means comprising an upwardly extending arm journaled at its lower end on said shaft, a manually movable cam pivotally connected to the upper end of the arm, a bracket rigidly attached to the shoe and pivotally mounted on said arm about a horizontal axis, means rigidly connected to the rock shaft and coacting with the cam for controlling movement of the shoe toward or away from the roll by movement of said cam, independently of said power driven means, said cam being formed to releasably retain the shoe at either of its positions of adjustment.

9. In an ironing machine, the combination with a rotatable roll, a shoe, a rock shaft, power driven means including a resilient connection for rocking said shaft, of means carried on said shaft and connected to the shoe for supporting and moving the latter into and out of cooperative relation to the roll upon rocking of said shaft, said supporting means comprising an upwardly extending arm journaled at its lower end on said shaft, a manually movable cam pivotally connected to the upper end of the arm, a bracket rigidly attached to the shoe and pivotally mounted on said arm about a horizontal axis, means rigidly connected to the rock shaft and coacting with the cam for controlling movement of the shoe toward or away from the roll by movement of said cam, independently of said power driven means, and means for adjusting said last mentioned means for altering the force of the resilient connection of the power driven means for varying the effective pressure of the shoe on the roll when in engagement therewith.

10. In an ironing machine, the combination with a rotatable roll, a shoe, a rock shaft, power driven means including a resilient connection for rocking said shaft, of means carried on said shaft and connected to the shoe for supporting and moving the latter into and out of cooperative relation to said roll, upon rocking of the shaft, said shoe supporting means comprising an upwardly extending arm journaled at its lower end on said shaft, a manually movable cam pivotally connected to the upper end of the arm, a bracket rigidly attached to the shoe and pivoted to said arm on a horizontal axis, means rigidly connected to the rock shaft and coacting with said cam, spring means acting on the arm and adapted upon the adjustment of the cam in one position, for moving the arm rearwardly to back the shoe away from the roll, and means for adjusting said cam coacting means for altering the force of the resilient connection of the power driven means, for varying the effective pressure of the shoe on the roll when in engagement therewith.

11. In an ironing machine, the combination with a rotatable roll, a shoe, a rock shaft, power driven means including a resilient connection for rocking said shaft, of means carried on said shaft and connected to the shoe for supporting and moving the latter into and out of cooperative relation to the roll upon rocking of said shaft,

12. In an ironing machine, the combination with a rotatable roll, a shoe, a rock shaft, power driven means including a resilient connection for rocking said shaft, of means carried on said shaft and connected to the shoe for supporting and moving the latter into and out of cooperative relation to the roll upon rocking of said shaft, said supporting means comprising an upwardly extending arm journaled at its lower end on said shaft, a manually movable cam pivotally connected to the upper end of the arm, a bracket rigidly attached to the shoe and pivotally mounted on said arm about a horizontal axis, means comprising a lever arm rigidly attached to the shaft, a member slidably mounted in the arm and having opposite ends cooperatively engaging said lever and said cam for controlling movement of the shoe toward or away from the roll, by movement of said cam, independently of said power driven means, and means for varying the relation of said lever and slidably mounted member for altering the force of the resilient connection of the power driven means for varying the effective pressure of the shoe on the roll when in engagement therewith.

13. In an ironing machine, the combination with a rotatable roll, a shoe, a rock shaft, power driven means including a resilient connection for rocking said shaft, of means carried on said shaft and connected to the shoe for supporting and moving the latter into and out of cooperative relation to the roll upon rocking of said shaft, said supporting means comprising an upwardly extending arm journaled at its lower end on said shaft, a manually movable cam pivotally connected to the upper end of the arm, a bracket rigidly attached to the shoe and pivotally mounted on said arm about a horizontal axis, means comprising a lever arm rigidly attached to the shaft, a member slidably mounted in the arm and having opposite ends cooperatively engaging said lever and said cam for controlling movement of the shoe toward or away from the roll, by movement of said cam, independently of said power driven means, an adjustable screw for varying the relation of said lever and slidably mounted member for altering the force of the resilient connection of the power driven means for varying the effective pressure of the shoe on the roll when in engagement therewith, and a spring associated with the screw for maintaining it in a desired position of adjustment.

14. In an ironing machine, the combination with a rotatable roll, a shoe, a rock shaft, power driven means for rocking said shaft, of means carried on said shaft and connected to the shoe for supporting and moving the latter into and out of cooperative relation to the roll upon rocking of said shaft,

- out of cooperative relation to the roll upon rocking of said shaft, said supporting means comprising an upwardly extending arm journaled at its lower end on said shaft, a manually movable cam pivotally connected to the upper end of the arm, a bracket rigidly attached to the shoe and pivotally mounted on said arm about a horizontal axis, means rigidly connected to the rock shaft and coacting with the cam for controlling movement of the shoe toward or away from the roll by movement of said cam, independently of said power driven means, an upwardly extending control handle telescopically connected to said cam for swinging it about its pivot connection, and a detent carried by the cam for releasably retaining said handle in extended position of 15 adjustment.
- 15 15. In an ironing machine, the combination with a rotatable roll, a shoe, a rock shaft, power driven means for rocking said shaft, of means carried on said shaft and connected to the shoe for supporting and moving the latter into and out of cooperative relation to the roll upon rocking of said shaft, said supporting means comprising an upwardly extending arm journaled at its lower end on said shaft, a manually movable cam pivotally connected to the upper end of the arm, a bracket rigidly attached to the shoe and pivotally mounted on said arm about a horizontal axis, means rigidly connected to the rock shaft and coacting with the cam for controlling movement of the shoe toward or away from the roll by movement of said cam, independently of said power driven means, and a control handle connected to the cam for moving it about its pivot connection.
- 20 16. In an ironing machine, the combination with a rotatable roll, a shoe, a rock shaft, power driven means for rocking said shaft, of means carried on said shaft and connected to the shoe for supporting and moving the latter into and out of cooperative relation to the roll upon rocking of said shaft, said supporting means comprising an upwardly extending arm journaled at its lower end on said shaft, a manually movable cam pivotally connected to the upper end of the arm, a bracket rigidly attached to the shoe and pivotally mounted on said arm about a horizontal axis, means rigidly connected to the rock shaft and coacting with the cam for controlling movement of the shoe toward or away from the roll by movement of said cam, independently of said power driven means, and an upwardly extending control handle telescopically connected to said cam for swinging it about its pivot connection.
- 25 17. In an ironing machine, the combination with a rotatable roll, a shoe, a rock shaft, power driven means for rocking said shaft, of means carried on said shaft and connected to the shoe for supporting and moving the latter into and out of cooperative relation to the roll upon rocking of said shaft, said supporting means comprising an upwardly extending arm journaled at its lower end on said shaft, a manually movable cam pivotally connected to the upper end of the arm, a bracket rigidly attached to the shoe and pivotally mounted on said arm about a horizontal axis, means rigidly connected to the rock shaft and coacting with the cam for controlling movement of the shoe toward or away from the roll by movement of said cam, independently of said power driven means, an upwardly extending control handle telescopically connected to said cam for swinging it about its pivot connection, and a socket on said arm adapted to receive the end of said handle in telescoped position, for locking said last mentioned means, arm and cam against relative movement.
